UNITED STATES PATENT OFFICE.

FREDERICK H. WOLKENHAUER, OF BENSENVILLE, ILLINOIS.

FURNACE.

Application filed February 15, 1919. Serial No. 277,211.

To all whom it may concern:

Be it known that I, FREDERICK H. WOLKENHAUER, a citizen of the United States, and a resident of the city of Bensenville, county of Du Page, and State of Illinois, have invented certain new and useful Improvements in Furnaces, of which the following is a specification.

My invention relates to improvements in furnaces, and has for its object the provision of an improved construction of this character adapted to induce thorough combustion of fuel and thus prevent smoke and permit of economical consumption of fuel, the present invention constituting an improvement over that disclosed in my prior application filed September 24, 1917, Serial No. 192,901, the present application being directed in part to subject matter disclosed in said prior application.

Other objects will appear hereinafter.

The invention consists in the combinations and arrangements of parts hereinafter described and claimed.

The invention will be best understood by reference to the accompanying drawings forming a part of this specification, and in which,

Fig. 1, is a longitudinal section on the line 1—1, Fig. 2, through the forward portion of a boiler furnace embodying the invention,

Fig. 2, is a view of the invention, partly in section, on the line 2—2 of Fig. 1.

Fig. 3, is a longitudinal sectional view of the forward portion of the furnace on the line 3—3 of Fig. 2.

Fig. 4, an enlarged detail view of the forward portion of the grate employed in the furnace.

Fig. 5 is an enlarged detail view of one end of the grate support and operating mechanism; and,

Fig. 6, a partial top plan view of one forward corner of said grate.

The preferred form of construction, as illustrated in the drawings, comprises a suitable boiler furnace provided with a suitable fire chamber 6, a return flue boiler 7 and a draft flue 8, as indicated. The grate frame 9 is arranged in the fire chamber 6 and is mounted on bell cranks 10 on posts 11 therein. The bell cranks 10 are connected by links 12 with operating handles 13 situated at the front of the furnace, all substantially as disclosed in my

prior Patent No. 1,160,233, granted November 16, 1915. The grate frame 9 carries on one side a rack bar 14, and on its opposite side a rack bar 14^a, upon which a series of mutilated gears 15 and 15^a are arranged to rock or roll. The gears 15 are provided with side flanges 15^b projecting beyond the gear teeth thereon and adapted to embrace the sides of the rack bars, thus serving to maintain rolling relation between said gears and rack bars, and gears 15^a are provided with similar flanges 15^c.

Each of the gears 15 is provided with a depending rocker arm 16 having a plurality of bolt holes 16^b therein adapted to receive bolts 17^b which serve to pivotally connect links 17 therewith. Similarly each of the gears 15^a is provided with a depending rocker arm 16^a having a plurality of bolt holes 16^c therein adapted to receive bolts 16^c which serve to pivotally connect links 17^a therewith. The gear members are divided into two sets 15, 15^a, each set consisting of every other one of the gear members on both sides of the grate frame, and respective rocker arms 16 and 16^a for each set of gear members are pivotally and adjustably connected by bolts 17^b and 16^c with the corresponding links 17 and 17^a whereby each set of gear members may be rocked or operated independently of the other, as indicated. An operating handle 19 is connected with one set of links 17, and consequently, with one set of gear members 15, and another operating handle 18 is connected with the other set of links 17^a and gear members 15^a, so that said sets of gear members may be readily rocked or rolled upon the rack bars when desired, either simultaneously or independently. Grate bars 20 and 21 are mounted upon the gear members 15 and 15^a. The grate bars 20, constituting one set, are provided on their under sides with rack bars 20^b engaging and rolling upon the corresponding set of gear members 15, and the grate bars 21 are similarly provided on their under sides with rack bars 21^b similarly engaging and rolling upon the other set of gear members 15^a. The grate bars 20 and 21 are arranged in overlapping relation, as indicated, so as to be capable of moving longitudinally with respect to the grate and laterally with respect to each other.

The grate bars 20 and 21 are provided with perforations 22 and 23 for the passage

of the draft and the discharge of ashes. By this arrangement, it will be observed that grate bars 20 and 21 may be alternately shifted forwardly by manipulating the handles 18 and 19, and then simultaneously shifted rearwardly to effect rearward feeding of the fuel on the grate and also agitation of said fuel to discharge the ashes therefrom. Likewise, it will be observed that the relative movements of the grate bars gradually decrease toward the rear of the grate itself, so that the movement of the fuel on the rear of the grate is not so rapid as that upon the forward portion thereof. There is, of course, always relatively more fuel on the forward portion of the grate than on the rearward portion, or rather, the fuel introduced onto the forward portion of the grate is larger in bulk than the same fuel by the time it reaches the rear portion thereof, so that by providing for faster feed on the forward portion of the grate a uniform bed for fuel may be maintained over the entire grate. By adjusting the connections between the links 17 and 17^a and the rocker arms 16 and 16^a, the extent of movement of the grate bars may be adjusted as desired, to meet the requirements of various qualities of coal, and thus adapt the furnace for varying conditions.

An apron 24 is hinged to the forward wall portion of the fire chamber 6 and rests loosely on a rod 24' connecting the forward portions of one side of links 17^a, thus permitting of vertical adjustments of the grate, but compelling passage of the draft therethrough. A similar apron 25 is hinged to the forward grate bar 25' which is rigidly secured to the grate frame 9, said apron 25 resting loosely upon the apron 24 to permit of the vertical adjustments.

A bridge wall top 26 is rigidly mounted on the rear end of the grate frame 9, and an apron 27 is mounted upon a rocker shaft 28 to seal the gap between the rearmost grate bar and said bridge wall top. The apron 27 is operated by means of a rocker arm 29 and an operating handle 30, as indicated, to permit passage of draft when desired, and also to discharge accumulation of ashes.

A hollow fire arch 31 depends from the top of fire chamber 6 and is equipped with a plurality of discharge openings or slits 32 arranged transversely in the lower side thereof, as shown. The interior of arch 31 is connected by means of a discharge pipe 33 provided with a valve 34 with the discharge of a blower casing 35 mounted as shown, and operable by means of a pulley 36. The blower casing is provided with an intake communicating with the atmosphere controlled by a valve 37 operated by an arm 38 and also with an intake 39 equipped with a similar valve leading into the draft flue

8 and whereby either air from the atmosphere, or smoke from the flue 8, or a mixture of the two, may be discharged into fire arch 31 and thence into fire chamber 6, immediately onto the fuel thereon, thus promoting combustion and thorough consumption of the smoke.

A branch discharge pipe 40 provided with a valve 41 leads from pipe 33 into the smoke flue 8 above blower 35, whereby, when desired, a blast of air may be introduced into said smoke flue to increase the draft therein and thus promote combustion.

An apron 42 formed in hinged collapsible sections is swingingly connected to depend from the forward portion of grate frame 9, and is equipped with an operating handle 43 for manipulating or adjusting the same. A blower casing 44 has its intake 45 arranged in registration with an opening 46 in the upper forward side wall of the fire chamber 6, as shown. The blower 44 is arranged to be operated by means of a pulley 47 and has its discharge 48 arranged to discharge downwardly in a flue 49 in the side wall of the furnace and leading to a plurality of ports or openings 50 under the grate in the fire chamber. By this arrangement a draft may be induced to withdraw a portion of the smoke and gas evolved from the coal on the forward portion of the grate and introduce them into the fire chamber below the grate and behind the apron 42 so that the same will have to pass upwardly through the grate for thorough and complete combustion.

By this arrangement the fuel on the forward portion of the grate will be first transformed into coke and the gases evolved therefrom thoroughly consumed in the furnace. Then this coke is gradually fed rearwardly along the grate under the fire arch where it is completely consumed by the combined actions of the drafts thereon. Any gases or smoke passing off through the flue may be withdrawn therefrom and introduced into the fire chamber through the fire arch 31 for further combustion. The parts may also be readily adjusted to maintain a uniform fire bed upon the grate.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A fire grate for furnaces comprising a plurality of movable grate bars, certain of

- said bars being connected together to form independently movable sets; means for moving said sets of bars simultaneously in one direction; and means whereby said bars 5 move away from each other during such simultaneous movement, substantially as described.
2. A fire grate for furnaces, comprising a plurality of movable grate bars, certain of 10 said bars being connected together to form independently movable sets; means for operating said grate bars; and means whereby said bars move apart different distances during such operation, substantially as described. 15
3. A fire grate for furnaces comprising two sets of grate bars shiftable laterally relative to each other in the same plane; gears engaging said grate bars for moving 20 same; and rocker arms of different lengths for shifting said grate bars different distances apart the extent of movement of said grate bars gradually decreasing from front to rear of said grate, substantially as 25 described.
4. A fire grate for furnaces comprising a grate frame; a plurality of movable grate bars mounted on said frame; a plurality of grate bar operating means mounted on said 30 frame, each alternate grate bar being connected to one of said operating means and the other of said grate bars being connected to the other of said operating means; and means for shifting the bars attached to one 35 of said operating means in one direction, and the other grate bars connected to the other of said operating means, in the opposite direction, or moving the same simultaneously in one direction when the operating 40 means are moved in unison, substantially as described.
5. A fire grate for furnaces comprising a frame; rack bars on opposite sides of said frame; gear members arranged to roll upon 45 said rack bars; rocker arms on said gear members; links connecting said rocker arms; and grate bars having racks meshing with said gear members, substantially as described.
6. A fire grate for furnaces comprising a grate frame; rack bars on said frame; gear 50 members arranged to roll upon said bars; side flanges on said gear members engaging the sides of said rack bars to maintain said gear members in rolling relation therewith; rocker arms on said gear members; links 55 pivotally connected with said rocker arms; grate bars having racks meshing with said gear members; and means for moving the links to actuate the rocker arms, substantially as described. 60
7. A fire grate for furnaces comprising a grate frame; rack bars along opposite sides of said frame; sets of gear members, each set comprising alternate pairs of gear members; rocker arms on gear members of each 65 set; links at each side of the frame, each link being connected with the rocker arms of one set; shiftable grate bars, one set of grate bars having racks engaging one set of gear members, and the other set of grate 70 bars having racks engaging the other set of gear members; and means for simultaneously actuating the links of each set to move the grate bars, substantially as described.
8. A fire grate for furnaces comprising a 75 grate frame; rack bars along the opposite sides of said frame; sets of gear members, comprising alternate pairs of opposite gear members; side flanges on each gear member engaging the sides of respective rack bars 80 to maintain said gear members in rolling relation therewith; rocker arms on said gear members; links at each side of the frame, each link being connected with the rocker arms of one set; sets of shiftable grate bars, 85 having racks thereon engaging said gear members; and means for moving the links of each set to actuate the rocker arms, substantially as described.

In testimony whereof I have signed my 90 name to this specification in the presence of two subscribing witnesses.

FREDERICK H. WOLKENHAUER.
